UNITED STATES PATENT OFFICE.

JOSEPH McEVOY, OF HAMILTON, MARYLAND.

SHAVING SET.

Application filed August 20, 1925. Serial No. 51,401.

To all whom it may concern:

Be it known that I, JOSEPH McEVOY, a citizen of the United States, residing at Hamilton, State of Maryland, have invented 5 certain new and useful Improvements in a Shaving Set, of which the following is a specification.

This invention relates to an improved article of manufacture which may be generally referred to as a shaving set, the same comprising a container for shaving cream, a plunger whereby the cream may be ejected, a brush for receiving the cream, and special compartments for holding the razor and 15 razor blades.

More specifically, the invention relates to a device comprising a cylindrical body, this being made into three sections, one section of which constitutes a top for the brush, the intermediate section of which forms a container for shaving cream, and the top section of which forms a special article holder.

The article holder is characterized by a central tubular barrel for accommodating 25 the operating stem of the plunger, and the intermediate section is constructed to accommodate a slide valve for controlling the passage of cream into the bristles of the brush.

30 Other objects and advantages of this invention will become apparent from the following drawing and description.

In the drawing forming a part of this application and in which like numerals are 35 employed to designate like parts through the same:—

Figure 1 is a central longitudinal section through a shaving set as constructed in accordance with the present invention.

40 Fig. 2 is a cross section approximately upon the plane of the line 2—2 of Fig. 1.

Fig. 3 is a cross section taken on the line 3—3 of Fig. 1.

Fig. 4 is a detail perspective view of the 45 slide valve, and

Fig. 5 is a perspective view of the head of the plunger.

As before intimated, the improved device embodies a central section 1, a bottom section 2, and a top section 3, the top and bottom sections being closed at their outer ends and adapted for telescoping detachable connection with the opposite ends of the central section.

55 Fitted in the top of the central section

is a closure 4 having a projecting flange 5 onto which the section 3 is removably fitted. Fastened to the bottom of the central section is a disk 6 having a depending flange 60 into which the correspondingly shaped block 7 and the upper end of the brush 8 is fitted. The dust cap 2 fits onto this depending flange. The block 7 and disk 6 are provided with alined openings through 65 which the paste or cream pass. As previously stated, the central section 1 provides a container for this cream.

In order to eject the cream I provide a plunger comprising disk 9 and a screw threaded stem 10 having swivel connection 70 with the center thereof. The stem is threaded through a spider 11 carried by the cover 4. Then there is knurled finger-piece 12 on top of the stem which serves for rotating the same. Interposed between the plunger disk and disk 6 is a slide valve 13 having openings which are adapted to align with the openings in the brush head when the valve is slid to operative position. The valve is provided with a finger 75 piece 14 to permit it to be conveniently operated.

Referring more particularly to the top section, it will be seen that this is provided with a central tubular guide 15 from which 80 webs 16 radiate, these webs dividing the section into a plurality of special compartments, one of which contains a razor blade handle 17, another one of which contains the blades 18, and the other one of which 85 contains the removable head 19 of the razor. In order to add to the utility, a mirror 20 is carried by the top of the section 3.

From the foregoing description it is obvious that in order to get the parts of the 90 razor out of the special container at the top, it is necessary to invert the device from the position shown in Fig. 1, at which time the part 3 may be pulled off. It is then replaced to function as a part of the handle 100 of the brush to be subsequently used. Before the section 3 is thus replaced, it is necessary to actuate the plunger which is then accessible by turning the knob 12. This ejects a small portion of the paste from the 105 container and passes it through the head of the brush to the bristles.

The operator must be sure that the slide valve is opened when the plunger is actuated 110 and then closed to prevent the further escape

of paste. Now the dust cap 2 can be removed and the bristles of the brush moistened to produce the desired lather.

A careful consideration of the description 5 in connection with the drawings will sufficiently, no doubt, enable persons familiar with articles of this design to obtain a clear understanding of the same. Therefore a more lengthy description is thought unnecessary. 10

While the preferred embodiment of the invention has been shown and described, it is to be understood that minor changes coming within the field of invention may be 15 resorted to if desired.

Having thus described my invention, what I claim as new is:—

1. In a structure of the class described, a cylindrical body comprising a pair of 20 separable sections, one of which is formulated to provide a special article holder,

and the other one of which is adapted to serve as a paste container, a plunger operable in said last named section, said plunger embodying a stem adapted for projection into the first named section. 25

2. In a structure of the class described, a cylindrical body comprising a central section, and a pair of end sections, said end sections being connected detachably 30 with the ends of the central section, one end of said section being formulated to provide a container for special articles, the other end section being adapted to function as a cover for a brush, a brush carried by the 35 central section, a plunger operable in said central section, said brush embodying a head provided with openings, and a slide valve carried by said section and cooperable with said opening. 40

In testimony whereof I affix my signature. JOSEPH McEVOY.
